US00D698675S

(12) **United States Design Patent**
Sallander

(10) **Patent No.:** **US D698,675 S**
(45) **Date of Patent:** **** Feb. 4, 2014**

(54) **DIAGNOSTIC APPARATUS**

(71) Applicant: **Martin Sallander**, Joenkoeping (SE)

(72) Inventor: **Martin Sallander**, Joenkoeping (SE)

(73) Assignee: **Autocom Diagnostic Partner AB**,
Trollhaettan (SE)

(**) Term: **14 Years**

(21) Appl. No.: **29/434,481**

(22) Filed: **Oct. 12, 2012**

(30) **Foreign Application Priority Data**

May 8, 2012 (EM) 002038356-0001

(51) **LOC (10) Cl.** **10-04**

(52) **U.S. Cl.**

USPC **D10/78**

(58) **Field of Classification Search**

USPC D10/78; D14/203.3, 203.7, 341, 426,
D14/507; 235/472.01, 472.03; 307/9.1;

(57) **CLAIM**

The ornamental design for a diagnostic apparatus, as shown and described.

DESCRIPTION

FIG. 1 is a perspective view of the invention;
FIG. 2 is an elevational front view of the invention;
FIG. 3 is an elevational back view of the invention;
FIG. 4 is an elevational end view as seen from the left in FIG. 2, the abbreviation "REC" being disclaimed;
FIG. 5 is an elevational end view as seen from the right in FIG. 2; and,
FIG. 6 is a side view as seen from below in FIG. 2, the side view as seen from above being identical.
